SANDAL OR SIMILAR ARTICLE

Robert Stile, New York, N. Y.

Application September 2, 1955, Serial No. 37,776

Term of patent 3½ years

(Cl. D7—7)

Figure 3 is a top plan view of the sandal shown in Figure 1, drawn to a larger scale, and showing the design in an open flat position.

I claim:

The ornamental design for a sandal or similar article, substantially as shown and described.
